UNITED STATES PATENT OFFICE.

WILLIAM B. RONEY, OF OMAHA, NEBRASKA, ASSIGNOR TO M. E. SMITH AND COMPANY,
OF OMAHA, NEBRASKA, A CORPORATION OF NEBRASKA.

CONVERTIBLE COLLAR.

1,213,954.

Specification of Letters Patent. Patented Jan. 30, 1917.

Application filed June 5, 1916. Serial No. 101,680.

To all whom it may concern:

Be it known that I, WILLIAM B. RONEY, a citizen of the United States, residing at Omaha, in the county of Douglas and State 5 of Nebraska, have invented certain new and useful Improvements in Convertible Collars, of which the following is a specification.

The object of this invention is to produce a collar for shirts, mackinaw coats, rain-10 coats and other garments, which shall be convertible at will into either one of two quite different styles. While the invention in its preferred form is embodied in a collar permanently attached to and forming a part 15 of a garment, the invention is not limited to such use. For example, it may be embodied in a separate collar adapted to be attached to the neck-band of a garment in the well-known manner.

20 In the accompanying drawings, Figure 1 is a front elevation of a portion of a shirt having attached thereto a collar embodying my invention, the collar being shown in so-called "military" position and the corners 25 of the outer portion being broken away to disclose the parts beneath. Fig. 2 is a view similar to Fig. 1, but showing the collar in so-called "negligée" position, and parts being broken out for the purpose above set 30 forth. Fig. 3 is a fragmental front elevational view showing the collar turned up and the two adjacent or overlapping portions of the shirt spaced away from each other to better disclose the structure. Fig. 35 4 is a section in the plane of line 4—4 of Fig. 3, single thicknesses of the cloth being shown for the sake of clearness.

When the invention is embodied in a collar permanently attached to a shirt, the 40 neck-band of the shirt constitutes the inner portion of the collar, the outer portion being folded down about the inner portion in the usual way. If the invention be embodied in a separate collar, however, the inner portion 45 of such collar would fit around the outside of the neck-band of the shirt, the outer portion of the collar being folded down about said inner portion.

Referring more specifically to the preferred embodiment shown in the drawings, the invention will be described in detail 50 without any intention of limiting the same to this embodiment, the scope of the invention being pointed out in the appended 55 claims.

The body of the shirt is indicated by the reference numeral 5, 6 being the usual opening extending down the front of the shirt, the adjacent edges of the shirt overlapping at this opening. The neck-band is indicated 60 at 7 and the collar proper at 8, the collar, neck-band and shirt body being sewed together in any common or preferred way.

One end 9 of the neck-band is extended beyond the adjacent end of the collar forming 65 a tab to overlap the opposing end of the neck-band, and the tab 9 is secured by fastening means, preferably in the form of a button-hole 10 in the tab 9 and a button 11 secured to the opposed end of the neck-band. 70

A tab 12 is secured to the upper edge of the tab 9 and the adjacent portion of the neck-band in such position that the tab 12 may span the opening between the adjacent 75 ends of the collar when the shirt is closed. Fastening means are provided for securing the tab 12 to the opposed ends of the collar, said fastening means preferably being in the form of button-holes 13 in the opposite 80 ends of the tab and buttons 14 sewed to the undersides of the collar adjacent to its opposed ends.

When the tab stands up from the neck-band and is secured to the buttons 14, the collar is held in the so-called "military" position as shown in Fig. 1, giving the effect 85 of a "stand-up" collar in front view. The utility and advantage of the arrangement do not reside alone in the appearance of the collar, but, as will be understood, the collar 90 when in the position shown in Fig. 1 affords greater protection to the throat, the tab 12 closing the space between the adjacent ends of the collar so that the latter is suitable 95 for use in cold or stormy weather.

When it is desired to wear the collar in the so-called "negligée" position, the tab 12 is folded down in front of the neck-band and one of the button-holes 13 is passed over the button 11, the other button-hole 13 being 100 secured by a button 15, which is sewed to the neck-band in proper position. The collar may now be folded farther down into the position shown in Fig. 2, which is the usual position occupied by collars in soft 105 shirts.

If the collar is made separate from the shirt, the tab 9 will, of course, not form a part of the neck-band of the shirt, as in the case of the permanently attached collar, but 110

the two tabs 9 and 12 may constitute an extension on the inner portion or fold of the collar.

I claim as my invention:

- 5 1. A convertible collar for garments having a tab to extend across the space between the adjacent ends of the collar, the collar comprising an inner portion and an outer portion adapted to fold down about said inner portion and in front of said tab, and a tab secured to the other tab and adapted to stand up to hold the collar in "military" position, or to fold down in front of the first tab to allow the collar to assume a "negligée" position, and suitable securing means for the second tab.
- 10 2. A soft folded collar having an inner portion and an outer portion, a tab connected to one end of the inner portion, a tab foldably connected to the upper edge of the first tab so as to be foldable downwardly into position in front of the first tab, and means for detachably securing the opposite ends of the second tab.

3. A shirt having a soft collar permanently attached thereto and having a tab secured adjacent to one end of the collar and adapted to overlap the opposed end, a tab secured to the first mentioned tab and arranged to stand up to hold the collar in "military" position or to fold down alongside the first tab to allow the collar to occupy a "negligée" position, a button and button-hole for securing the first tab to the opposed portion of the shirt, the second tab having two button-holes at horizontally opposite ends, two buttons secured to the underside of the collar and adapted to enter said two button-holes and hold the second tab in upstanding position, and a fourth button arranged to receive one of the button-holes on the second tab when the latter is folded down, the other button-hole on said second tab being arranged to receive the first mentioned button.

In testimony whereof, I have hereunto set my hand.

WILLIAM B. RONEY.
